UNITED STATES PATENT OFFICE

2,171,331

ELECTRIC CORD ASSEMBLY FOR VACUUM
CLEANERS OR THE LIKEElwood E. Folsom, Jr., Trumbull, Conn., assignor
to General Electric Company, a corporation of
New York

Application July 1, 1937, Serial No. 151,430

1 Claim. (Cl. 173—322)

The present invention relates to a cord assembly for vacuum cleaners and the like wherein there is provided a handle to which is connected an electric cord which in turn is connected through an electric switch to a motor or other electrical device to be controlled.

In such apparatus, a relatively long cord is provided to give a suitable operating range for the vacuum cleaner and this cord drags back and forth across the floor as the cleaner is used. As a result, considerable pulling strains are put on the mechanical connection between the cord and the handle and also there is considerable flexing of the cord adjacent to the handle.

One object of the present invention is to provide an improved construction and arrangement for mechanically connecting a cord to a vacuum cleaner handle or the like which is simple in construction and easy to assemble on the handle and which attaches the cord to the handle in a manner such that it is firmly held by the handle so that no strain can be put on the electrical connections between the cord and the switch.

A further object of the invention is to provide a construction wherein the cord is held on the handle or the like in a way such that flexing of the cord adjacent to the handle is distributed over a length of the cord so that the wires of the cord are protected against breakage due to flexing.

For a consideration of what I believe to be novel and my invention, attention is directed to the following specification and the claim appended thereto.

In the drawing, Fig. 1 is a side elevation of a vacuum cleaner provided with the construction embodying my invention; Fig. 2 is a longitudinal sectional view of a portion of the vacuum cleaner handle at which the cord is connected, and Fig. 3 is a detail perspective view of a part of the cord and the parts through which it is connected to the handle.

Referring to the drawing, 1 indicates the body of a vacuum cleaner to which is attached a handle 2 for propelling the cleaner across the surface to be cleaned and 3 indicates a vacuum cleaner bag which is connected to the discharge nozzle 4 of the cleaner at one end and supported by a hook 5 at the other end. On handle 2 are hooks 6 on which the cord 7 may be wound when the cleaner is not in use. The construction so far described is to be taken as typical of any suitable vacuum cleaner construction.

The handle 2 is formed from a hollow steel tube and adjacent to its outer end is provided

with an opening 8 on its under side normally closed by a cover plate 9 fastened in place by screws 10. The handle is round and cover plate 9 is made to conform to the contour of the handle. In the present instance, one of the screws 5 10 serves to hold in place also the hook 5 for the upper end of the vacuum cleaner bag, as shown particularly in Fig. 2. In cover plate 9 is an opening 11 through which the cord enters the handle and an opening 12 through which 10 the switch handle 13 projects.

Switch handle 13 forms a part of any suitable type of switch indicated at 14 and which in the present instance is shown as being attached to cover plate 9 by means of screws 15. The binding posts for the switch are indicated at 16 and the movable element of the switch is indicated at 17. The switch shown is of known construction and since its specific construction forms no part of the present invention, further 20 description is unnecessary. It is to be taken as typical of any suitable switch for controlling an electric circuit.

In the present instance, opening 11 is shown as being surrounded by an outwardly projecting 25 collar 18 providing a recess in which is located a metal washer 19.

On cord 7, directly adjacent to its end, there is provided a sleeve or casing 20 formed of rubber or other suitable flexible material. Preferably it is molded directly on to the cord so as to form an integral part thereof. However, if desired, it may be formed separately and suitably attached to the cord by cementing it in place or otherwise. Sleeve 20 has an enlarged head 35 21 at its outer end and a tapered portion 22 which extends from the head along the cord, embedding the cord for some little distance from the head. Preferably the tapered portion 22 is molded or formed to have normally the curved 40 shape shown in the drawing so that it extends downwardly in the direction the cord normally takes in hanging down from the vacuum cleaner handle. Head 21 is provided with a shoulder 23 which fits against the outer surface of the wall 45 surrounding opening 11 and with a portion 24 which projects through such opening to a point inside the handle. The wall at opening 11 is of a thickness sufficient to hold firmly head 21 and prevent it from turning; and also to prevent the wall from cutting the head. On opposite sides of portion 24 are longitudinally extending grooves 25 which receive the two arms 26 of a yoke 27 for fastening the head in cover plate 9. The grooves 25 are so located that 55

when the yoke 27 is in position, as shown in Fig. 2, flange 23 is held tightly against the outer surface of the cover plate. Preferably opening 11 is of a contour other than round so that when 5 the head is in position therein, it is held from turning. In the present instance, opening 11 is shown as having opposite flat sides, portion 24 of head 21 having corresponding flat surfaces to fit against said sides. This serves to hold the 10 head from turning in the opening. At one end of yoke 27 is an upturned finger 28 which serves as a handle for use in inserting and removing the yoke.

In the use of the invention, the switch and 15 cord are attached to cover plate 9, the switch being attached by means of screws 15, and the cord being attached by means of the yoke 27 after which the conductors on the cord are connected to the binding posts 16 of the switch. 20 This forms then a unitary assembled construction which can be attached to the vacuum cleaner handle by placing the cover plate against the handle and inserting the screws 10, the switch and the inner end of head 21 projecting through 25 the handle opening 8.

By the foregoing construction, it will be seen that the cord is attached to the cover plate by merely inserting the portion 24 of the head through the opening in the plate and slipping the 30 yoke 27 into position. This is a thing which can be quickly and easily done. When thus connected, the cord is firmly attached to the handle and any pull on the cord will be taken by the yoke and cannot be transmitted to the switch

connections. Also, the tapered sleeve 22 serves to hold the cord in a curve of relatively large radius and any bending of the cord adjacent to the handle is taken by this radius. This serves to prevent sharp bending of the cord adjacent to the handle which might in time cause the 5 wires to become broken.

While I have particularly described my invention as being applied to a vacuum cleaner or the like, it is to be understood that the invention is 10 not limited thereto necessarily but may be used wherever found applicable.

What I claim as new and desire to secure by Letters Patent of the United States is:

In combination, a plate having an opening 15 therein, an electric cord, a sleeve of flexible resilient material secured to and surrounding said cord and having a head located in said opening, said head having a collar thereon engaging said plate on one side and opposed grooves therein 20 located on the other side of said plate, and a slideable yoke having arms of rigid material located in said grooves, said grooves being so located with respect to said collar that said arms will flex the resilient material of said head upon 25 insertion in said grooves whereby said arms are held in engagement with said plate, said yoke and collar gripping the opposite sides of said plate to secure said head in said opening with the electric cord passing through said opening, said 30 sleeve having a tapered portion extending from the head along said cord to form a strain relief for said cord.
